WILLIAM S. THOMSON, OF PLANTSVILLE, CONNECTICUT, ASSIGNOR TO THE H. D. SMITH & COMPANY, OF PLANTSVILLE, CONNECTICUT, A CORPORATION.

BEARING-GUIDE FOR GRINDING-MACHINES.

1,257,549.

Specification of Letters Patent. Patented Feb. 26, 1918.

Application filed April 26, 1917. Serial No. 164,603.

To all whom it may concern:

Be it known that I, WILLIAM STRATTON THOMSON, a citizen of the United States, residing at Plantsville, in the county of Hartford and State of Connecticut, have invented 5 certain new and useful Improvements in Bearing-Guides for Grinding-Machines, of which the following is a specification.

My invention relates to improvements in 10 bearing guides for grinding machines, and the object of my improvement is simplicity and economy in construction and convenience and efficiency in use.

In the accompanying drawing:—

15 Figure 1 is a front elevation of a grinding machine embodying my invention.

Fig. 2 is a side elevation of the upper part of the same.

20 Fig. 3 is a sectional view on the line $\alpha\alpha$ of Fig. 2.

Fig. 4 is a sectional view on the line $\beta\beta$ of Fig. 3.

25 Fig. 5 is a sectional view on the line $u\beta$ of Fig. 3.

Fig. 6 is a fragmentary view, on an enlarged scale, of certain parts shown in Fig. 5.

The grinding machine shown as embodying my invention corresponds to the one shown and described in the patent mentioned, and comprises a casing 10 in which is operatively housed a shaft 11 which projects outwardly therefrom and on the outer end of which is mounted a grinding or polishing wheel 12, and the operation of which 30 is controlled by a handle 13.

35 The casing 10 is a shell-like structure and comprises a body portion composed of a pedestal portion 14 having tapered front and rear walls and merging into the base 15 at the lower end and at the upper end merging into the box-like head 16, the upper end being closed by a cover 17.

40 The shaft 11 is mounted in ball bearings 19 provided in a pair of journal heads 20 positioned in the casing head 16. The driven pulley 21 is shrunk on the shaft 11 between the journal heads 20 and the belt 22 rests on the upper face thereof, and drops down-

wardly to the driving pulley on a counter shaft directly below the same. The shaft 50 11 projects through a vertical slot 23 in the end wall of the casing head 16 and is provided with means for being raised and lowered, a brief description of which will suffice for the present application. 55

Below the pulley 21 is a plate-like bridge 26 that serves as a brake for the pulley when dropped thereon.

The shaft 11 as stated is operatively supported by bearings 19 provided in the journal heads 20. The journal heads 20 comprise a head proper 28 provided with an axial bore 29 in which is positioned the shaft 11 and having vertical ways 30 at the front and rear, suitable for slidably engaging with 60 guide ways 31 secured to the casing head 16 by screws 32 and 33, and a neck 34 extending downwardly from the said head proper 28. The neck 34 is provided with a screw 65 threaded hole 35 extending upwardly from the lower end suitable for receiving the upper end of a supporting and adjusting stud 36.

One end of the supporting stud 36 is threaded left handed and the other right 75 handed, and the lower end thereof engages with the internally threaded boss 37 on the yoke 38. Below the boss 37 the yoke 38 is provided with a slot 39 which extends transversely relatively to the vertical axial plane 80 of the shaft 11 and supporting stud 36, and which is a fit for and in which is positioned the auxiliary shaft or rod 40. The two yokes 38 are in horizontal alinement and the auxiliary shaft 40 extends therethrough and the 85 ends thereof are secured eccentrically to the disks 41 rotatively housed in the bosses 42 in the side walls of the casing 10.

As the disks or eccentrics 41 are rotated the auxiliary shaft 40 is moved in an arc 90 and the same is accordingly raised and lowered as well as swung back and forth relatively to the vertical axial plane. The slot 39 permits of the cross-wise movement of the auxiliary shaft 40 while the yoke 38, stud 36, 95 and journal head 20 are maintained con-

stantly in the same axial and vertical plane, and the ways 30 and 31 permit of vertical movement of these parts responsive to the raising and lowering of the auxiliary shaft.

5 The handle 13 is mounted on one end of the auxiliary shaft 40, and a stop-pin 44 is provided to engage with the same to limit the movement and to hold the parts in the elevated position.

10 The ways 31 comprise strips of material of uniform cross-section and suitable length positioned in the casing head 16 and adjacent and parallel with the front and back walls 61 thereof. These have a V-shaped formation on the inner face 62 thereof and are flat along the outer face 63, and have a screw threaded hole 64 at about the middle of the outer face 63 suitable for receiving the supporting screw 32. These screws 32 pass 15 through holes 67 in the outer wall 61 and the heads 65 engage with the outer faces of the said outer wall 61, preferably in a counter bored seat 66 provided therefor.

15 The screws 33 are headless and are engaged with the screw threaded holes 68 in the walls 61 and engage with their inner ends against the outer face 63 of the track or way 31, and serve as backing screws in opposition to the middle supporting screws 32, there being 20 two backing screws 33, one above and one below the supporting screw 32 in each case.

25 As described, the tracks or ways 31 are substantially parallel with the walls 61 and they are in spaced relation thereto, being 30 spaced therefrom by a small space 69 sufficient with the limited freedom of movement permitted by the screw supporting means provided to permit of a slight adjustment of the said tracks to provide for properly guiding the journal heads 20 in their movement substantially in a vertical plane.

35 The neck 34 on the journal heads 20 is elongated, and the threaded upper end 70 of the stud 36 engaged therewith is correspondingly elongated, and the ways 30 on the body portion or head proper are also elongated and these parts coöperate to maintain 40 the yoke 28 on the same vertical plane, the body portion or head proper 28, stud 36 and yoke 38 being positively positioned as a unit.

45 As the box-like head 16 of the casing has vertical and parallel front and back walls 61 the guide ways or guide rails 31 are parallel to the said walls, and by making the casing head 16 slightly large I am enabled to provide the clearance space 69 already mentioned between the said walls 61 and the rails 31. By providing the clearance 69, and thus avoiding actual contact of the rails 55 31 with the opposed walls 61, the tracks 31 are properly supported in operative position without the necessity of finishing the opposed wall 61, which is left rough, just as cast, the casing structure being made of 60 cast iron.

As described the screws that support the tracks 31 comprise the tension screw 32 at the middle and a thrust screw 33 on each side thereof.

This is the preferred arrangement, although in some cases the arrangement of the screws may be reversed, by having two tension screws on the sides and a single thrust screw at the middle.

75 I claim as my invention:—

1. In combination in a grinding machine, a casing having a box-like head portion at the upper end, journal heads housed in the said head portion and having each a pair of ways, one on the front and one on the back wall, and a guide track for the said journal heads engaged with the said ways, and supported from the walls of the said head portion, and means for adjustably supporting the said tracks from the said walls comprising coöperating tension and compression screw mechanism.

80 2. In combination in a grinding machine, a casing having a box-like head portion at the upper end, journal heads housed in the said head portion and having each a pair of ways, one on the front and one on the back wall, and a guide track for the said journal heads engaged with the said ways, supported 85 from the walls of the said head portion, and means for adjustably supporting the said tracks from the said walls comprising coöperating tension and compression screw mechanism.

90 3. In combination in a grinding machine, a casing having a box-like head portion at the upper end, journal heads housed in the said head portion and having each a pair of ways, one on the front and one on the back wall, and a guide track for the said journal heads engaged with the said ways, supported 95 from the walls of the said head portion, and means for adjustably supporting the said tracks from the said walls comprising coöperating tension and compression screw mechanism, and the said means for supporting the said tracks from the said walls comprising in each case a set of screws 100

extending through holes in the said wall and composed of a tension screw at the middle and a pair of compression screws, one on each side of the said tension screw, the said tension screw having a head at one end engaged with the said wall and having the other end threaded into the said track, and the said compression screws having threaded 105 engagement with the holes in the said wall and having thrust engagement by the inner ends with the opposed face of the said track.

110 4. In a grinding machine, a casing having an unfinished inside wall, journal boxes housed therein, means for raising and lowering the said journal boxes, guide ways engaged with the said journal boxes, and means for supporting the said guide ways from the said inside wall, and the said last named means being operative to support 115 the said guide ways in spaced relation to the said inside wall.

120 5. In a grinding machine comprising a casing, journal boxes housed therein having means for being raised and lowered, guide ways engaged with the said journal boxes, and the said guide ways being supported by screws that penetrate the walls of the said casing, and which engage by their ends with the said guide ways.

125 6. In a grinding machine comprising a casing, journal boxes housed therein having means for being raised and lowered, guide ways engaged with the said journal boxes, and the said guide ways being supported by screws that penetrate the walls of the said casing, and which engage by their ends with the said guide ways.

130

5. In a grinding machine comprising a casing, journal boxes housed therein having means for being raised and lowered, guide ways engaged with the said journal boxes, and a plurality of screws penetrating the walls of the said casing, engaged with the said guide ways, and operative to hold the said guide ways in spaced relation to the said walls of the casing.
- 10 6. A grinding machine comprising a casing, a shaft provided with a pulley and a grinding wheel, bearings in the said casing and engaged with the said shaft, means for raising and lowering the said bearings, means for guiding the said bearings in a vertical plane comprising a plurality of tracks engaged with the said bearings and the said tracks supported from the said casing by means of a set of screws comprising a middle screw and a pair of screws one on each side of the said middle screw, and the

said screws being engaged with the said track so that the said middle screw is in opposition to the said pair of screws.

7. A grinding machine comprising a casing, a shaft, bearings in the said casing and engaged with the said shaft, means for raising and lowering the said bearings, and means for guiding each of the said bearings comprising a track engaged therewith, and means for supporting the said track comprising a middle screw, penetrating the wall of the said casing and engaged with a screw threaded hole in the said track and a pair of thrust screws, one on each side of the said middle screw, engaged with screw threaded holes in the said casing, and having ends in abutment with the face of the said track.
